PROTECTIVE DEVICE FOR
CLOTHESPRESSES

Jonathan N. Coulter and Bert Williams, Los Angeles, Calif., assignors to Kathleen A. Averill, Los Angeles, Calif.

Application September 8, 1937, Serial No. 162,883

6 Claims. (Cl. 74—614)

This invention relates to a protective device for clothes pressing machines. The object of the invention is to provide means for protecting the operator of steam clothespressing machines from escaping steam, without interfering with the normal operation of the machine.

This object is attained by the mechanism illustrated in the accompanying drawing, in which:

Fig. 1 is a perspective view of one form of the protective device of this invention;

Fig. 2 is an elevation, partly in section, showing details of the form shown in Fig. 1;

Fig. 3 is an end elevation of a clothes pressing machine in open position, equipped with this protective device;

Fig. 4 is a front elevation of the same;

Fig. 5 is an end elevation similar to Fig. 3, with the machine in closed position.

The invention consists of a movable fabric curtain which, by the movement of a reciprocable pressing member of the machine, is interposed in front of the pressing members when they are brought together, and is moved out of the way when they are separated. In the preferred embodiment of the invention, the fabric curtain is raised and lowered by rolling it upon a roller, which is rotated by any suitable means associated with the up and down movement of the reciprocable member. In a preferred form which is shown in the drawing, a rack and pinion device is used to rotate the curtain roller, but other equivalent means for accomplishing the same result may be employed.

Referring to the drawing, a preferred form of the invention consists of a frame 11 having bearing supporting arms 12 and 13, bearings 14 and 15, a shaft or roller 16 mounted in the bearings, and a fabric curtain 32 attached for rolling on the roller 16. Endwise movement of the shaft or roller 16 is controlled by the adjusting screw 17 with its lock nut 18 and the collar 20 with set screw 21. On an extension 22 of the roller shaft from one bearing, 15, is attached a pinion 23 having teeth 24 which is adapted to engage the rack 25 supported in a channel member 26. The rack 25 is held in mesh with the pinion 23 by the compression spring 27 placed around the spring shaft 28 which is slidably supported in the collar 29 held by the U-shaped member 30 whose two arms are rotatably engaged on the shaft extension 22 and positioned on the shaft extension by the collar means 31. The channel member 26 is attachable in hinged relation by the hinge 36 to a relatively fixed portion of the machine and

is slidably mounted in the slide member 37 attached to the spring shaft 28.

The application of the device of this invention to a pressing machine is shown in Figs. 3, 4, and 5, in which a conventional press is diagrammatically represented. Numerous variations of this general type of pressing machine are in use, and our protective device is applicable to all of them having the general characteristics indicated. In general the pressing machine consists of a main frame 40, a work table 41, a stationary pressing member 42, a movable pressing member 43 pivotably supported at 44 on an upright member 45 of the main frame, having a counterweight 46 and a handle 47 for moving the member 43 up and down. Levers for controlling the pressure between the pressing members, for steam and for vacuum control etc., are represented, conventionally at 48 and 49. The movable pressing member 43 is provided with a foraminous cover on its working or under surface, usually of fine wire mesh, and pipe connections for delivery of wet steam to the hollow head so that the steam may be blown, when desired, through the wire mesh onto the garment being pressed. Usually the garment is arranged on the lower buck, the movable member is lowered into contact with the garment, wet steam is blown on the garment to moisten it, after which the steam is shut off and the pressing operation completed by increasing the pressure by means of a foot lever, and sometimes by the application of suction to the surface of the hollow stationary pressing member whereby the moisture is removed, leaving a pressed dry cloth surface.

When the garments between the pressing members are subjected to the wet steam as above described, the steam, at least in part, escapes around the edges between the pressing members, and part of this comes in contact with the operator's hands, face and body, and is dangerous, and disagreeable. Our device prevents this unsatisfactory working condition by automatically interposing a protective curtain 32 between the operator and the pressing members.

As shown in the drawing, our device is adapted to be attached to machines already built and in operation, and for this purpose the U-clamps 50 may be used to attach the device to the brackets 51 of the handle 47. Other attaching means may of course be used, including bolting or fastening to the movable member 43.

When the pressing members are apart, as shown in Figs. 3 and 4, the curtain 32 is nearly completely rolled up on the roller 16, a small por-

tion being held in hanging position by the weighted rod 33. In this position, the rack 25 on the pinion 23 is near its uppermost end. The opposite end of the rack, or of the channel member 5 26 supporting the rack 25 is attached to the rear side of the work table 41 by the hinge member 36. After the clothes have been arranged on the stationary pressing member 42, the operator pulls down the movable member 43 by means 10 of the handle 47; and the rack 25 rotates the pinion 23 and in turn the curtain roller 16 and the curtain 32 is unwound and takes the position shown in Fig. 5. In this position of pressing members and curtain, the wet steam is admitted 15 to the clothes and any escaping steam is deflected by the curtain away from the operator. When the steam has been shut off, and after the remaining steps of the pressing operation have been completed, the movable member 43 is raised 20 out of the way from further adjustments on the stationary member of the garment being pressed. Simultaneously with the raising of the movable member 43 by the handle 47, the rack 25 rotates the pinion 23 in the opposite direction and winds 25 the curtain 32 on the roller 16. At no time does the curtain interfere with the operations of the pressing machine, and it effectively deflects the escaping steam away from the operator.

While a rack and pinion mechanism has been 30 shown for revolving the roller for the curtain, other equivalent means may be used such as cord and pulley, differential pulley, and the like.

While one particular preferred embodiment of the invention has been described, other arrangements 35 are possible, and the invention is to be restricted only insofar as is necessitated by the prior art and the appended claims.

We claim:

1. In a clothespressing machine having pressing members at least one of which is oscillatable, a vertically hanging non-rigid steam-deflecting curtain arranged to cut off the space between the pressing members from the operator when the pressing machine is closed or nearly closed, and means actuated by the oscillatable pressing member for putting said curtain between the machine and the operator when the pressing members are brought together and for removing it when the pressing members are separated.
2. In a clothespressing machine having a pressing member oscillatably movable relative to the base of said machine, a vertically hanging non-rigid steam-deflecting curtain arranged to be interposed between the machine and the operator thereof, a winding roller for said curtain

mounted on the machine, and means actuated by said member to revolve said roller.

3. In a clothespressing machine having an oscillatable pressing member, a vertically hanging non-rigid steam-deflecting curtain arranged to be interposed between the pressing members and the operator of said machine, a winding roller for said curtain mounted on said member, a pinion on said roller, and means associated with a stationary part and the oscillatable member of the machine adapted to revolve said pinion when said member is raised and lowered.

4. In a clothespressing machine having an oscillatable pressing member, a vertically hanging non-rigid steam-deflecting curtain arranged to be interposed between the machine and the operator thereof, a winding roller for said curtain mounted on said pressing member, a pinion on said roller, and a rack hingedly attached to said machine adapted to rotate said pinion whereby to raise the curtain when said member is raised, and to lower the curtain when said member is lowered.

5. In a clothespressing machine having an oscillatable pressing member, a vertically hanging non-rigid steam-deflecting curtain arranged to be interposed between the machine and the operator, a winding roller for said curtain mounted on said member, a pinion gear on said roller, a rack, a hinge means between said rack and said machine, said rack and pinion adapted to wind and unwind the curtain when the reciprocable member is raised and lowered.

6. A safety device for attachment to a clothespressing machine having an oscillatable pressing member, comprising a shaft, bearings for said shaft, bracket means for supporting said bearings, a hanging fabric curtain attached to said shaft for winding thereon, a pinion gear on said shaft, a rack bar having rack teeth at one end adapted to engage the teeth of the pinion gear and having hinged attaching means at the other end for attachment to a fixed part of the pressing machine, a sliding guide member for said rack bar, a U-shaped member rotatably attached on the end of the shaft adjacent said pinion gear, spring means between said U-shaped member and said sliding guide member for holding the rack teeth of said rack bar in operative position on said pinion gear and adapted to allow sliding contact between said rack bar and said guide, and means for attachment of the bracket means to the said oscillatable pressing member of said machine.
